SKI FASTENING

Karl Kinzl, Vienna XIII, Austria

Application December 14, 1937, Serial No. 179,754
In Austria February 5, 1937Section 3, Public Law 690, August 8, 1946
Patent expires February 5, 1957

4 Claims. (Cl. 280—11.35)

1

This invention relates to a control device for ski fastenings by which the heel pull member which forms a closed loop may be tensioned and released as required.

The control device according to the invention has two hooks for alternatively anchoring the heel pull member.

The invention further provides a control device for this purpose comprising an anchorage member, a lever pivoted to the anchorage member, a hook for engaging the heel pull member resiliently connected to the anchorage member, and a hook also for engaging the heel pull member pivotally connected to the lever.

The arrangement enables a diagonal pull to be changed over to a normal pull simply by opening the lever of the control device. When the control lever is thus operated the hook of the control lever releases the cable, which thenceforth is engaged by the resilient hook only, which, owing to its springiness, enables the shoe heel to be lifted off the ski to a greater extent, as is required at normal pull. If subsequently diagonal pull is again to be set, it is merely necessary to close the control lever so that the second pull member will also be engaged by the hook thereof.

The invention further comprises the provision of separate means on the aforesaid control device which enable the latter to be finely adjusted to be able to adapt the fastening to the size of the shoe used and to the desired tension.

In the accompanying drawing an embodiment of the invention is illustrated by way of example.

Figure 1 shows the control device in side elevation and Figure 2 in plan.

Referring to the drawings, here a slideway 22 having inwardly extending flanges 23 is secured to the ski 24 and guides the U-section slide 25, on the block 26 of which a tensioning lever 27 is pivotally mounted. A pull element 12 pivotally connected to the lever 27 is formed with a hook 13 at its free end, which is capable of engaging a yoke 15 attached to the cable 37. Further, the slide 10 has mounted thereon a hook 14, which is slidable in the longitudinal direction of the ski and the movement of which in the direction of the shoe is damped by a spring 141 disposed within the slide.

If diagonal pull is required the tensioning lever 27 is brought to the closed position 27' with the hook 14 engaging the cable 37 and the hook 13 on the pull member 12 engaging the yoke 15 (position 13', 12', 15' respectively). If, however, for example when climbing up a hill, normal pull is required, the tensioning lever is opened where-

2

by the hook 13 on the pull element 12 releases the yoke 15 and therewith the cable 37, so that the latter is only held by the resilient hook 14, whereby it becomes possible to lift the heel of the shoe much higher.

Adjustment of the slide 25 in accordance with the size of the shoe and the tension required is effected with the screw bolt 31. The screw bolt 31 is pivotally mounted on a pin 32 in the slide 10 25, so that said screw bolt is rockable in a vertical plane. The slideway 22 has upbent sides 34 at its rear part, which have inwardly extending flanges or lugs 35 at their rear ends.

These flanges engage in an annular groove 33 15 at the nut 36, which is thus held in a freely rotatable but axially non-slidable manner by the flanges 35. Owing to the pivotal connection of the screw bolt 31 to the slide 25, it is possible to lift slightly the nut 36 with the bolt 31 for the purpose of easier manipulation.

What is claimed to be new is:

1. In a ski fastening wherein a heel pull member forms a closed loop capable of being tensioned and released, a control device comprising 25 an anchorage member, a lever pivoted to the anchorage member, a hook for engaging the heel pull member resiliently connected to the anchorage member, and a hook also for engaging the heel pull member pivotally connected to the lever.

30 2. In a ski fastening wherein a heel pull member forms a closed loop capable of being tensioned and released, a control device comprising a fixed guide, a slide adjustable in the guide, means releasably locking the slide in adjusted position, a lever pivoted to the slide, a hook for engaging the heel pull member resiliently connected to the slide, and a hook also for engaging the second pull member pivotally connected to the lever.

35 3. In a ski fastening device wherein a heel pull member forms a closed loop capable of being tensioned and released, a control device comprising a fixed guide, a screwed nut rotatably mounted by the guide, a slide in the guide, a bolt extending from the slide into engagement with the 45 screwed nut whereby rotation of the latter adjusts the position of the slide, a lever pivoted to the slide, a hook for engaging the heel pull member resiliently connected to the slide, and a hook also for engaging the heel pull member pivotally connected to the lever.

40 4. In a ski fastening wherein a heel pull member forms a closed loop capable of being tensioned and released, a control device comprising a fixed guide, a screwed nut rotatably mounted by the 45 guide, a slide in the guide, a bolt extending from

the slide into engagement with the screwed nut whereby rotation of the latter adjusts the position of the slide, a lever pivoted to the slide, a hook for engaging the heel pull member resiliently connected to the slide, and a hook also for engaging the heel pull member pivotally connected to the lever.
